UNITED STATES PATENT OFFICE

WALTER HEHN, OF CHICAGO, ILLINOIS

COMBINED STAMPING CHASE AND PALETTE

Application filed December 10, 1930. Serial No. 501,189.

This invention relates to improvements in a combined stamping chase and palette and it consists of the matters hereinafter described and more particularly pointed out in the appended claims.

The primary object of the invention is to provide a device especially adapted for use in book binderies for stamping or compressing titles and other data as a whole upon individual books, whereby such stamping may be more rapidly carried out at a cost much less where such titles and data are stamped, a line at a time as is now the custom.

A further object of the invention is to provide a chase and palette adapted to hold a plurality of lines of type or equivalent impression members and which lines are automatically centered during the locking in thereof.

Still another object of the invention is to provide a chase and palette wherein the lines of type or impression members may be readily changed as the occasions demand and which automatically centers said various lines irrespective of their different lengths.

These objects of the invention as well as others, together with the many advantages thereof will more fully appear as I proceed with my specification.

In the drawings:—

Fig. 1 is a view in bottom plan or from the impression face of a combined chase and palette embodying my invention.

Fig. 2 is a fragmentary perspective detail view of a part of the frame of the improved chase and palette.

Fig. 3 is a perspective view of a part of one of several clamping blocks embodied in the device.

Fig. 4 is a perspective view of a part associated with the part shown in Fig. 3 to provide a complete clamping block.

Fig. 5 is a transverse vertical sectional view through the device as taken on the line 5—5 of Fig. 1.

Fig. 6 is another transverse vertical sectional view through the device as taken on the line 6—6 of Fig. 1.

Fig. 7 is a longitudinal vertical sectional view through the device as taken on the line 7—7 of Fig. 1.

Fig. 8 is a view in side elevation of the device.

Heretofore, it has been the practice in stamping or impressing the desired data upon individual books for library purposes, to set up the type in a chase in a single line, the type being centered therein by the practiced eye and then locked in place by quoins and associated elements. After the line of set-up type was heated, the operator made the impression with the aid of gold leaf or the like, centering the set-up line on the book, by the eye. Thereafter the used line was removed, the next one made up and set in the chase which was then heated after which the second impression was made and similar operation carried on for each line.

Thus where an entire library of individual books was to be stamped, the many operations and the vast amount of time consumed is apparent.

In general, my improved chase and palette comprises a grid like frame, provided with the usual handle like bar by which it may be manipulated and carried about during and after the necessary heating thereof. This frame includes a plurality of transversely extending, spaced, parallel pressure bars, and with each bar is associated an aligning flange or plate and a pair of type or impression member clamping blocks, which are capable of equal movement toward and away from each other along the associated pressure bar.

Preferably each pair of blocks is engaged with a right and left hand threaded rod which may be operated from one end to rotate the same in either direction so that the desired movement is imparted to the associated pair of blocks. Each line of type or impression members is composed upon the associated bar up against the aligning flange or plate between the associated clamping blocks.

Thereafter upon turning the rod, the blocks are moved toward and into lateral engagement therewith to securely lock them.

in place and centrally of the frame. The next line is made upon and positioned upon its associated pressure bar and then the associated rod is actuated to move the 5 clamping blocks into engagement therewith and center the same with respect to the first set-up and clamped line of type or impression members, irrespective of its length. Thus each line is set up until all data for 10 the desired book is composed and then the chase as a whole is heated and the entire impression is made upon the book at one time.

Thereafter, the various type or impression 15 members are removed and new or different ones substituted therefor, according to the data to be impressed upon the next book when the operation is as before mentioned.

Referring now in detail to that embodiment of the invention, illustrated in the accompanying drawings:—1 indicates as a whole the body of the chase which comprises an open rectangular frame 2, a backing plate 3 closing what is normally the top of the 25 frame when the chase is in use, and a grid like plate 4 secured to what is normally the bottom of the frame when the chase is in use.

The frame 2 comprises end bars 5—5 and 30 side bars 6—6 and in the inner face of the latter is formed a plurality of transversely extending grooves 7.

The backing plate 3 which is unperforated is of an area approximating that of said frame, as is the grid like plate 4 which is provided with a plurality of transversely extending, pressure receiving bars 8—8. The frame, backing plate and grid like plate are secured in assembled relation by corner 40 bolts and nuts 9 as best shown in Figs. 1 and 5.

Secured centrally to the backing plate is a lever like bar 10 and the free end of this bar has a heat insulating handle 11. Associated with each pressure bar is a flange like plate 12 of a depth considerably greater than that of the frame as a whole. Each plate 12 is provided with shorter end parts 13 of a depth equal to that of the frame 2, 50 and these end parts are engaged in registering grooves 7 in opposite side members of said frame as best shown in Fig. 6. These flange like plates are held in position in the frame, against movement by the backing plate 3 and grid like plate 4 respectively. When thus held in place, each plate 12 is engaged with that surface of an associated pressure bar which is the top surface thereof when viewed in the position as shown in 55 Fig. 1.

Extending between both side members 6 of the frame and arranged in suitable openings of the pairs of openings 14—14 in each of said side members are rods 15, having 60 right and left hand threads 16 and 17

respectively thereon. These rods are held against endwise movement by pairs of locking nuts 18 engaging the outer face of each side member and the extremity 19 of each rod is formed to receive a crank 20 by which 70 said rods may be turned or rotated. As shown herein, both extremities of each rod are squared for that purpose to accommodate right and left handed operators but as is apparent only one extremity of each rod 75 is all that is required to be so squared.

In Fig. 7 it will be noted, that alternate rods are all disposed in one plane and the intermediate rods are disposed in another plane but this is only for convenience in saving space.

Associated with each threaded rod is a pair of clamping jaws or blocks 21—21 and each jaw is preferably made in two jaw or block parts 22 and 23 respectively as best 85 shown in Figs. 3 and 4. The part 22 of the jaw or block comprises a rectangular base 24 of desired length and of a width approximating the spacing between adjacent flange like plates 12, and a flange 25 of a narrower 90 width and length. In the base 24 is a pair of longitudinally threaded openings 26. Associated with each block part 22 is a block part 23 in the form of a plate with a flange 27 at one end to engage with that end of 95 the flange 25 of the part 22 terminating short of the base. This jaw or block part 23 carries pilot pins 28 to engage in pilot openings 29 in the flange 25 and the two parts are further secured together by a 100 screw 30. It is pointed out that when the part 23 which is of a depth less than that of the associated flange 25, is secured thereto, a groove 31 is provided for partially embracing a pressure bar 8 for sliding guiding 105 bearing thereon as best shown in Fig. 7.

Of course, it is apparent that in a pair of such clamping blocks, the openings 26 in one will have left hand threads and the openings in the other will have right hand 110 threads.

The various pairs of blocks are adapted to clamp in place, the desired lines of type or impression members 32. These type or impression members which are usually made of brass, are of a depth that when engaged with their bases against or upon an impression bar 8, have their opposite and impression ends, extending beyond the free edge of the associated plate like flange 12 as best 115 shown in Fig. 7.

When the desired line of type or impression members have been composed upon a bar 8 they are aligned thereon up against a plate like flange 12 between the blocks of an associated pair of blocks or jaws 21. In thus composing a line of type, no care need be exercised so far as centering the same between the associated blocks is concerned.

So soon as the line of type or impression 120

members has been composed, the crank 20 is applied to the squared end of the rods and turned in that direction which will cause the associated blocks or jaws to travel on the pressure bar toward each other. Thus movement is continued until both jaws of the pair bring up against the ends of the line of type or impression members to tightly clamp the same between them.

0 The next line of type or impression members is composed and even though the same be of a length different from that of the first mentioned line, by reason of the equal movement of both blocks or jaws of the associated pair, said next line is centered with respect to the first line.

As shown in Fig. 1, the chase will hold ten lines of type which is sufficient for any ordinary data to be stamped upon individual books. However, in this particular instance less than ten lines are employed to set forth the title of the book and the name and the author, the various lines all being centered with respect to the chase and with respect to each other.

After the various lines of type or impression members have been composed and locked in the position shown, the chase is heated. When heated, it is by means of the lever handle applied to the holder of a press and is then brought into stamping or impression relation with respect to the book to be operated upon.

By means of my improved devices, any data may be quickly changed, ready for the next book and so on. The device fulfills a long felt want in binderies making a specialty of stamping the title, author and other data upon individual books of a library or the like as it eliminates much hand work that calls for long experience, and materially reduces the amount of time required over practices heretofore followed to attain the same end.

5 While in describing the invention, I have referred in detail to the form, arrangement and construction of the various parts, the same is to be considered merely as illustrative only so that I do not wish to be limited thereto except as may be specifically set forth in the appended claims.

I claim as my invention:—

1. A device of the kind described comprising a frame, including a plurality of parts providing supports upon which a plurality of lines of impression members may be composed, and means for clamping each line of impression members and for centering said lines with respect to each other.

10 2. A device of the kind described comprising a frame including a plurality of parts providing supports upon which a plurality of lines of impression members may be composed and means for clamping each line of impression members and for centering said

lines in said frame and with respect to each other.

3. A device of the kind described embodying therein a frame including a plurality of transversely extending, parallel spaced bars each providing a support for a line of impression members, and means movable on said bars toward and away from each other to clamp against the associated line of impression members and for centering the same with respect to adjacent lines of impression members.

4. A device of the kind described embodying therein a frame including a plurality of transversely extending, parallel spaced bars each providing a support for a line of impression members, means providing an aligning flange for each bar for engagement by the impression members of each line arranged on said bars and means having a guided movement on said bars and operable for movement toward and away from each other for clamping said line of impression members upon the associated bar and against the associated aligning flange and for centering each line with respect to the others.

5. A device of the kind described embodying therein a frame including a plurality of transversely extending, parallel spaced bars each providing a support for a line of impression members, means providing an aligning flange for each bar for engagement by the impression members of each line arranged on said bars and means having a guided movement on said bars and operable for movement toward and away from each other for clamping said line of impression members upon the associated bar and against the associated aligning flange and for centering each line with respect to the others and with respect to said frame as a whole.

6. A device of the kind described embodying therein a frame including a plurality of transversely extending, parallel spaced bars each providing a support for a line of impression members, a pair of clamping blocks associated with each bar and movable thereon toward and away from each other into and out of clamping engagement with the associated line of impression members thereon and means operatively engaged with each pair of blocks and extending through at least one side of the frame and there formed for engagement with an actuating element.

7. A device of the kind described embodying therein a frame including a plurality of transversely extending, parallel spaced bars each providing a support for a line of impression members, a pair of clamping blocks associated with each bar and movable thereon toward and away from each other into and out of clamping engagement with the associated line of impression mem-

bers thereon, a right and left hand threaded rod operatively engaged with each pair of blocks and journalled in the sides of the frame and means for imparting a turning 5 movement in either direction to said rod.

8. A device of the kind described embodying therein a frame including a plurality of transversely extending, parallel spaced bars each providing a support for a 10 line of impression members, a pair of clamping blocks associated with each bar and movable thereon toward and away from each other into and out of clamping engagement with the associated line of impression 15 members thereon, a right and left hand threaded rod operatively engaged with each pair of blocks and journalled at its ends in the sides of said frame and means for holding each rod against endwise movement 20 when turned, each rod being formed at one end beyond one side of said frame to receive an element for imparting rotation thereto.

9. A device of the kind described embodying therein a frame, a backing plate for one 25 face thereof, a second plate for the other face thereof and including a plurality of transversely extending, spaced parallel bars, an aligning flange associated with each bar 30 and held in position with respect thereto, a pair of clamping blocks formed for sliding guided engagement upon each bar toward and away from each other and means for moving said blocks toward and away from 35 the middle of each bar.

10. A device of the kind described embodying therein a frame, having side members with slots on the inner surface thereof, a backing for one face of the frame, a second 40 plate for the other face of said frame and including a plurality of transversely extending, parallel spaced bars, an aligning flange associated with each bar and having end parts arranged in aligned slots in the 45 side members of the frame, means for securing said frame, backing and second plate together in a position holding said aligning plates in place and means providing a pair of blocks with sliding guiding bearing upon 50 each bar.

11. A device of the kind described embodying therein a frame, having side members with slots on the inner surface thereof, a backing for one face of the frame, a second 55 plate for the other face of said frame and including a plurality of transversely extending, parallel spaced bars, an aligning flange associated with each bar and having end parts arranged in aligned slots in the 60 side members of the frame, means for securing said frame, backing and second plate together in position holding said aligning plates in place, means providing a pair of blocks movable upon each bar toward and 65 away from each other and rods journalled

in said side members of the frame in planes between those of the slots therein, each of said rods having right and left hand threads thereon operatively engaged with the associated block and operable upon a turning 70 movement in the proper direction to move said blocks toward and away from each other upon the associated bar.

In testimony whereof, I have hereunto set my hand, this 6th day of December, 75 1930.

WALTER HEHN.
